SPACE CODED LINEAR ARRAY ANTENNA
Frank S. Guteber, Wayne Township, Passaic County,
N.J., assignor to International Telephone and Tele-
graph Corporation, Nutley, N.J., a corporation of
Maryland

Filed Oct. 23, 1961, Ser. No. 146,906
5 Claims. (Cl. 343—844)

This invention relates to antenna systems and more particularly to methods and equipment for obtaining any desired antenna pattern from a linear antenna array.

Array antennas of a variety of types are well known in the prior art. These prior art antenna arrays have been of several types. One type has utilized a number of equally spaced antenna elements to build up an array. This type of simple array of equally spaced antenna elements which are provided with equal amplitudes of driving current or voltage produce an antenna pattern whose shape can be controlled to only a very limited degree. A typical response of such an equally spaced antenna system with equal amplitude driving power at each individual element results in the well known $\sin x/x$ radiation pattern. Although such a pattern can produce a narrow central lobe, it suffers from the defect that the first side lobe is quite high in amplitude compared to the main lobe, and in fact the first side lobe is down by only $1/4.72$ or approximately 13 db. The values of the central or main lobe and the side lobes relative to each other can not be changed no matter how large a number of elements is provided in such an array. The relative values of the side lobes and the central lobe are fixed by the geometry of the system.

To improve over such equally spaced linear array antennas, the prior art has resorted to a number of expedients which have been only partly successful. Schelkunoff, for example, in United States Patent No. 2,286,839 shows an array antenna utilizing a number of equally spaced individual antenna elements. Schelkunoff provides both an individual amplitude control device and an individual phase control device for each of the individual antenna elements that compose his array. In general the amplitude of the driving current which is applied to each of the antenna elements is different from the amplitude in other antenna elements. Likewise the phase of the signal applied to each of the individual antenna elements is in general different from that of other elements in the array. Schelkunoff provides a systematic manner of choosing the particular amplitudes and phases supplied to the elements of his array. However, these amplitudes and phases follow a polynomial distribution. Although this procedure resulted in a somewhat improved antenna pattern, it has a number of extremely serious drawbacks. The most important of these is the fact that, since different amplitudes of signal must be supplied to different individual elements, either transmitting stages of different individual design must be supplied, or else large amounts of available power must be dissipated in power dividing networks etc. to provide the required ratio of feed powers. Also, individual phase control must be supplied to each element. In addition to these practical disadvantages, serious computations problems arise in attempting to design such an antenna array which utilizes individual elements unequally supplied with power at different phases, because the effect of an individual antenna element on the array as a whole is by no means readily ascertained from the equations required for the design.

Other prior art systems have attempted to provide antenna arrays which likewise utilize the method of supplying unequal amplitude and phase signals to the individual antenna elements. For example, binomial coefficients have been utilized to provide the amplitudes supplied to

2

individual elements in the array. Such array antenna systems likewise suffer from the practical defects of supplying unequal power and phase to the individual elements and from the computational difficulties involved which make difficult or impossible the actual detailed design of a particular desired antenna pattern.

A further disadvantage of the prior art systems has resulted from the fact that many of these arrays are built up out of elements spaced in three dimensions from each other. That is, elements are placed at certain points within a given area and also above or below the plane of this area at certain elevations. The difficulty here arises when it is attempted to improve the radiation pattern of the antenna by utilizing a large number of individual elements. The addition of new elements does not produce any effect which is readily predictable from the type of mathematical analysis provided in the prior art array systems, and in fact it is often difficult to determine where, or in what part of the array, additional elements should be provided.

Therefore, it is an object of my invention to provide a systematic method for increasing the number of elements in an antenna array to systematically improve the resulting radiation pattern obtainable.

It is another object of my invention to provide a space coded linear array antenna which utilizes individual antenna elements which are fed with equal amounts of power and with equal amounts of driving current which may be supplied at the same phase.

It is a further object of my invention to provide an array antenna system which obtains the maximum benefit possible from a given number of individual elements utilized to build up the array to provide an optimum radiation pattern in space utilizing this given number of elements.

It is a feature of my invention to provide an antenna array composed of a number of individual antenna elements which is an integral power of the base 2. A particular number of individual antenna elements are spaced unequally from each other so as to cause a predetermined effect on the antenna radiation pattern due to each set of elements which make up the array.

It is another feature of my invention to provide a space coded linear array antenna in which all of the individual antenna elements may be driven with equal amounts of current or voltage and wherein the phase of the signal supplied to all of the individual antenna elements may be the same. The individual antenna elements in this array are placed at predetermined unequal distances from each other according to a systematic set of design equations which allow the production of an arbitrary desired antenna pattern utilizing a particular predetermined number of antenna elements.

It is another feature of the invention to provide a space coded linear array antenna whose design may readily be extended to provide a three dimensional radiation pattern in space with no further additional computation. This method allows the particular unequal coded locations of the individual antenna elements of a first set of elements in the array to be extended to provide the pattern for the entire array. The entire two dimensional array may be driven by supplying equal power at the same relative phase to all of the individual antenna elements.

The above mentioned and other features and objects of my invention will become more apparent by reference to the following description taken in conjunction with the accompanying drawings in which:

FIGURE 1 is a diagram illustrating the geometry of an array antenna, as viewed from the top, which is useful in deriving the equations involved;

FIGURE 12 is a plot of the field radiation intensity E_t of the antenna of FIGURE 10 vs. the physical space angle θ .

Referring now to FIGURE 1, the general relationship is shown between the elements of a linear array which are unequally spaced from each other and showing the meaning of the space angle θ . θ represents the direction of a line v drawn from the array along a particular direction which is of interest at the moment. The angle θ represents the angle between x , the axis of the antenna, and the line v which may be moved about to examine any particular direction which is of interest. The radiated wave front is perpendicular to the line v as shown. For a linear array antenna, it is ordinarily sufficient to design for values of θ which run only between 0 and 90 degrees. Because of symmetry, the antenna appears to produce the same pattern whether one stands on one side of the axis x or the other. Likewise, if the disposition and number of antenna elements is even and their distribution is symmetrical, the second quadrant will produce a pattern which is the same as the pattern in the first quadrant and is in fact the mirror image of the pattern in the first quadrant. For this reason, it is necessary only to work with values of θ between 0 and 90 degrees for linear array antennas. In the most general case, one would examine θ for 360° of azimuth, but this is not necessary here. The first two elements of the array are shown separated by a distance d_1 . The distance $d_1 \sin \theta$ represents the difference in distance that two wave fronts starting from the two elements have traveled along the line v located at the angle θ . The different distances

which are traveled by the wavefronts from the individual elements results in differences in phases of the radiation from the individual elements at points removed from the antenna, as is well known in the antenna theory. There are a number of ways to characterize an expression for the total radiation due to an array, such as shown in FIGURE 1, which has N elements. One representation which is particularly useful for our purposes is given in Equation 1.

10 (1)

$$|E_t = A_0 + A_1 e^{j\psi} + A_2 e^{j2\psi} + A_3 e^{j3\psi} + \dots + A_{n-1} e^{j(n-1)\psi}|$$

Where E_t equals the intensity of the electric field radiated by the antenna, $A_0=1$, e is the base of the natural logarithms, all of the amplitude coefficients A_1 through A_{n-1} are either 1 or 0, and ψ is given by Equation 2.

$$(2) \quad \psi = \frac{2\pi}{\lambda} d \sin \theta$$

In Equation 2, ψ = the phase of radiation; λ equals the wavelength at the particular operating frequency of the antenna; θ is the physical space angle, as explained above; and d is an elemental uniform distance which represents an equivalent average uniform separation of the antenna elements.

The actual antenna elements of the array are in general unequally spaced from each other, but the distance d is an equivalent uniform spacing which I use to demonstrate the utility of my method of creating the array. In all the equations e is the base of the natural logarithms. Alternately, the radiation from a linear array antenna may be represented by Equation 3:

$$(3) \quad E_t = A_0 + A_1 e^{jN_1\psi} + A_2 e^{jN_2\psi} + A_3 e^{jN_3\psi} + A_{n-1} e^{j(N-1)\psi}$$

where the terms N represent coded relative spacings of the individual antenna elements, the first element being located at the position N_1 , the second element being located at the position N_2 , and so on. Either approach is equally valid, and it makes no difference which is used in the end result in the array.

To understand the rest of the derivation, it is well to give a general explanation of the technique which will be employed to create the array. Suppose, for example, that there are a given number of elements, say four, in an existing array. For any one of these four elements, another element can be added, that is, a fifth element, such that at any given space angle θ , the radiation from the fifth element would be exactly out of phase, that is, 180° out of phase, with the radiation from the first of the four elements. Likewise a second element, that is a sixth element, may be located a certain distance from the second element of the first four, so as to produce radiation which is exactly out of phase from the radiation produced by the second element of the original array of four elements. In other words, if the position of the first four elements of the existing array were given as N_1, N_2, N_3, N_4 then to extend the array by adding elements which produce zero radiation along a given direction in space, that is, at a given value of θ , elements would be added at distances determined as follows:

$$(4) \quad N_5 = N_1 + S_1$$

Thus, the position of the fifth element, that is, the position N_5 , is equal to the position of the first element N_1 , plus an added increment of distance S_1 . S_1 is so chosen to result in radiations which are completely out of phase from the elements N_1 and N_5 .

Likewise to provide a null in the radiation pattern, that is, zero radiation intensity at some value of θ , it is necessary to place an additional element the same incremental distance S_1 from each of the original elements in the array. Thus, in Equation 5:

$$(5) \quad N_6 = N_2 + S_1$$

Two more elements N_7 and N_8 are likewise placed in the same manner from the elements N_3 and N_4 . This tech-

nique of building up the array allows a design wherein at certain points in space at certain values of the angle θ , nulls are produced in the radiation pattern. It remains however to provide a systematic manner of choosing the incremental distances, such as S_1 , which must be added to the existing members of the array to produce the next set of members to increase the size of the array.

Referring again either to Equation 1 or Equation 3, we can write Equation 6:

$$(6) \quad \text{Arg } Z^1_N = \text{Arg } Z_N + 180^\circ$$

Where $Z_N = ANe^{jN\lambda\psi}$, a general term of the series given in Equation 1 or Equation 3. For any particular element in an existing array, a second element can be placed a particular distance from this first element, such that the radiation is 180° out of phase. This is the meaning of Equation 6. Therefore, for the next element, that is $N_{(x+1)}$, the relationship given in Equation 7 prevails:

$$(7) \quad N_{(x+1)}\psi = N_x\psi + 180^\circ$$

Equations 8, 9 and 10 solve for the position N_{x+1} :

$$(8) \quad N_{(x+1)} = N_x + \frac{180^\circ}{\psi}$$

$$(9) \quad N_{(x+1)} = N_x + \frac{180^\circ}{\frac{360^\circ}{\lambda} \sin \theta}$$

$$(10) \quad N_{(x+1)} = N_x + \frac{\lambda}{2d \sin \theta}$$

Thus, the next element is given in terms depending upon the previous element. In the quantity

$$\frac{\lambda}{2d \sin \theta}$$

the quantity 2 occurs because an out-of-phase condition has been chosen.

It is now necessary to provide a method of picking S_1 (of Equation 4) in terms of some design parameter that will allow a relatively easy manipulation of the design parameters with a minimum of calculation. At the same time, it is desirable to pick the design parameter in such a manner that the total effect of all of the elements in the array when it is considered at any particular given value of θ can be predicted. I now choose an arbitrary design factor K in such a manner. Consider Equation 11.

$$(11) \quad \text{Let } \frac{1}{K} = \frac{\lambda}{d \sin \theta}$$

Equation 11 is true by definition, that is, K was chosen in this manner. From Equation 77 substituted back into Equation 10, Equation 12 follows:

$$(12) \quad \text{Then } N_{(x+1)} = N_x + \frac{1}{2K}$$

Equation 12 states that to form a new element position $N_{(x+1)}$, we add the quantity $1/2K$ to the previous element position N_x . In other words, S_1 equals $1/2K_1$. Equation 12 thus indicates the basic method for building up the array. Each time it is desired to extend the array by increasing the number of elements, the size of the array will be doubled. For each existing element, one more element will be added. Each of the added elements will be the distance $1/2K$ from its own corresponding previous existing element.

However, the quantity K can still be chosen in such a manner as to facilitate design procedures and to make as simple as possible the computations involved. For this reason, the following steps are taken. First, θ_0 is defined as the physical space angle where the first null of the antenna radiation pattern occurs. Now K_1 is made equal to 1 at the first null when θ equals θ_0 . By doing this,

the entire design of the array is "normalized." This will become more apparent as the explanation proceeds. With K equal to 1 and θ equal to θ_0 , then Equation 11 becomes Equation 13A.

$$5 \quad (13A) \quad 1 = \frac{\lambda}{d \sin \theta}$$

Equation 13A may now be rewritten as Equation 13B:

$$10 \quad (13B) \quad d = \frac{\lambda}{\sin \theta_0}$$

Equation 13B is now substituted into Equation 2 above to form Equation 14A:

$$15 \quad (14A) \quad \psi = \frac{2\pi}{\lambda} \frac{\lambda}{\sin \theta_0} \sin \theta$$

Equation 14A may also be written as Equation 14B substituting 360° for 2π .

$$20 \quad (14B) \quad \psi = \frac{360^\circ}{\lambda} \frac{\lambda}{\sin \theta_0} \sin \theta$$

From Equations 11 and 13B, Equations 15 and 16 may be obtained which show that K equals the ratio of $\sin \theta$ divided by $\sin \theta_0$:

$$25 \quad (15) \quad K = \frac{d \sin \theta}{\lambda} = \frac{\lambda}{\sin \theta_0} \frac{\sin \theta}{\lambda}$$

$$(16) \quad K = \frac{\sin \theta}{\sin \theta_0}$$

30 In other words, K is the ratio of the sine of any particular value of the space angle θ divided by the sine of the particular space angle where the null of the first lobe occurs, that is, the main lobe of the antenna radiation pattern. Thus Equation 14B can be rewritten by substituting K for

$$35 \quad \frac{\sin \theta}{\sin \theta_0}$$

as given by Equation 16:

$$40 \quad \psi = (360)K$$

The actual physical position of an element is equal to

$$\frac{\lambda}{360} N_x \psi$$

45 which, when the above value of ψ is substituted, may be written:

$$(17) \quad \frac{\lambda}{360} N_x \psi = \frac{\lambda}{360} N_x (360)K = \lambda N_x \frac{\sin \theta}{\sin \theta_0}$$

50 Now the actual physical coded spacings of the antenna array occur for $\sin \theta = 1$. In other words at θ equal to 90° . This is because at θ equal to 90° , the array is being examined directly broadside, that is from a side elevational view. Thus Equation 18 gives the physical coded space relationship.

$$(18) \quad N_x \psi \frac{\lambda}{360^\circ} = N_x \frac{\lambda}{\sin \theta}$$

Equation 18 is given in units of wavelengths, that is, 60 depending on the particular value $\sin \theta_0$ which is chosen, an actual physical array can be built. θ_0 it should be remembered, is the angle in space where the first null occurs for the antenna radiation pattern. Equations 12, 17 and 18 provide the basis for computing all of the required quantities to build the array with any arbitrary antenna pattern. To illustrate this, Equation 12 will be rewritten providing an actual index X which indicates how the particular values of K which have been chosen as arbitrary design factors are incorporated to build up 65 the next step of the array.

70 The basic procedure is this: To form an array of larger size, the number of elements in the array must be doubled. This is because each existing element of the previous array must have added to it, that is, placed some distance from it which we have denoted by S , another element which

will produce at some particular space angle θ , the radiation which is 180° out of phase with the radiation from this corresponding element of the previous array. Thus, the number of elements in the array must be a power of 2. An array built according to my method therefore may consist of 2 elements, 4 elements, 8 elements, 16 elements, 32 elements, 64 elements, and so on, but the number of elements in the array will always be a power of 2. Likewise, for each additional power of 2 which is created when the size of the array is doubled, another arbitrary value for the design constant K may be chosen. In other words, in an array which has 16 individual antenna elements, four values of K may be chosen arbitrarily. This is because 2 to the 4th power is equal to 16, and the array is in a sense composed of four "sets" of elements which have been spaced in relationship to each other to produce the result according to my method.

Equations 19, 20 and 21, written below, symbolize this procedure. In Equation 19, N_1 is the first element of an existing array. To increase the size of the array, another element must be added. This is the term $N_{(2^x+1)}$ which is the first new element of the next set which is being added to the array. This term $N_{(2^x+1)}$ represents an element which must be spaced a distance $1/2K_{(x+1)}$ from N_1 .

Stated in another way, Equation 19 shows how to locate the first additional element when the array is being increased from a given size. Likewise, Equation 20 shows how to add the second new element of the increased array. Equation 21 shows how to add the last element to increase the array to its final size.

It should be noted that the subscripts are powers of 2. X is simply an index number which takes on integral values as the size of the array increases. For an array which has two elements, X is equal to 0; for an array that has four elements, X is equal to 1; for an array that has 8 elements, X is equal to 2; for an array that has 16 elements, X is equal to 3; and so on. Every time the size of the array is doubled, that is, every time X increases one unit, this allows one additional value of K to be arbitrarily chosen.

$$(19) \quad N_{(2^x+1)} = N_1 + \frac{1}{2K_{(x+1)}}$$

$$(20) \quad N_{(2^{x+2})} = N_2 + \frac{1}{2K_{(x+1)}}$$

$$(21) \quad N_{(2^{x+2})} = N_{(2^x)} + \frac{1}{2K_{(x+1)}}$$

Where $X=0, 1, 2, 3$, etc.

A discussion of the first embodiment of our invention shown in FIGURE 2 and some examples will make clear the procedure which can actually be performed extremely rapidly with pencil and paper in most cases. Referring to FIGURE 2, there is shown a linear array antenna composed of 16 individual antenna elements numbered 1 through 16. This drawing is in correct relative scale, that is, the correct relative spacing of all the elements is actually given in FIGURE 2. A scale is provided in "normalized" electrical degrees running from 0 degrees, which is the reference value of the first element 1, up to 450° . The location of the last element 16 is at 435° electrical degrees. The values used for K to create this array are K_1 equal to 1, K_2 equal to $\frac{1}{2}$, K_3 equal to 2 and K_4 equal to 4. Thus with an array of 16 elements, four values of K may be chosen arbitrarily. A translation device 17, which might be a transmitter or receiver, for example, is shown connected to the 16 elements of the array by feed lines such as 18, 18a, 18b, and so on. Equal amounts of power are supplied to each one of the 16 elements in the antenna array; likewise the phase of the signal from the device 17 is exactly the same for each of the 16 elements.

I shall now illustrate with some examples how this array of FIGURE 2 is designed and will show the re-

sulting design curves and the resulting radiation pattern in space. Next to each one of the elements in the array, the identifying position notation such as N_1, N_2 etc. has been written, so that the elements of the array can be identified.

It should be noted that, although once the array is built, it makes no difference what any particular element is called, in actually designing the array, the numbering of the elements is important until the design has been completed. This is the reason that element N_9 , for example, is next to element N_1 . Likewise the next element proceeding from left to right is N_5 and then N_3 . The reason for this will be made clear by the example. In actual physical constructions, since all of the elements are the same, and since each is fed with the same amount of power at the same phase, it makes no difference whether or not their notation is preserved.

Code No. 1 is given below:

TABLE I

Code No. 1 (shown in FIGURES No. 2 and No. 5)
16 element code with forced nulls chosen at:

$$K_1=1, K_2=\frac{1}{2}, K_3=2, K_4=4$$

25 the phase codes at $K=1$ are:

$N_1=0^\circ$	$N_9=45^\circ$
$N_2=180^\circ$	$N_{10}=225^\circ$
$N_3=120^\circ$	$N_{11}=165^\circ$
$N_4=300^\circ$	$N_{12}=345^\circ$
$N_5=90^\circ$	$N_{13}=135^\circ$
$N_6=270^\circ$	$N_{14}=315^\circ$
$N_7=210^\circ$	$N_{15}=255^\circ$
$N_8=390^\circ$	$N_{16}=435^\circ$

30 Actually the values listed are N_1, N_2 etc. in this table are $\psi N_1, \psi N_2$. In other words, these are normalized electrical degrees and they do not yet represent physical distances, although they are in the correct relative proportion to each other to represent physical distances. I have used a shorter notation, such as N_1 , for the brevity of presentation. These values here are the same as those shown in FIGURES 2 (and 5), as can be verified by the reader by simple comparison. I will show by example how these values for this first antenna array were obtained. First, for convenience, the first element of the array N_1 , element 1 of FIGURE 2 is taken as having zero phase, that is, it is the reference element. All other elements will be positioned in reference to this first element. Utilizing Equation 19, it is readily perceived where the next element is to be placed. The next element N_2 will now provide an array of two elements, this allows exactly one value of K to be chosen. K has been equal to 1, as indicated before, to provide a normalized design for convenience. Thus, from Equation 19, it may be seen in Equation 22B, below, that the second element should be placed 180° out of phase with the first element.

$$(22A) \quad N_2 = N_1 + \frac{1}{2K_1} = \frac{1}{2}$$

$$60 (22B) \quad N_2 = \frac{1}{2}(360^\circ) = 180^\circ$$

65 This is actually the basic technique of our invention: to place each successive element 180° out of phase with its corresponding element from the previous array. It should be noted that Equations 19 and 22A actually give the calculation of the positions in terms of the design parameters K . K , in the present instance equals 1. Multiplying by 360 then converts into electrical degrees, since there are 360 electrical degrees for one wavelength of radiation. However, this is an arbitrary calculation, and if it is more convenient, the values may be left in the form shown in Equation 22A, namely $\frac{1}{2}$, for example, and the conversion need be done only at the end. For the time being, the reader's visualization is greatly assisted by converting into electrical degrees.

It should also be remembered that these electrical degrees to be converted into the distances in space depend obviously on the actual operating frequency chosen for the antenna, since the wavelength changes physically for different frequencies. However, the values given in the Table I also depend upon the particular design parameter θ_0 which can also be chosen at will, as was indicated in Equation 16. This will also be made clear by the later discussion.

So far the array consists of two elements, namely, N_1 and N_2 . It is now desired to increase the size of this array to four elements. To do this, consider Equation 19. The index X is now equal to 1, in other words, a second value K_2 for the designed parameter K can be chosen. I have chosen K_2 to equal $\frac{1}{2}$. Thus from Equation 19, Equation 23 can be written:

$$(23A) \quad N_3 = N_1 + \frac{1}{2K_2} = N_1 + \frac{1}{3}$$

$$(23B) \quad N_3 = \left(0 + \frac{1}{3}\right)(360)^\circ = 120^\circ$$

The position of the third element of our array can be calculated. It should be remembered that each time a power of two is reached in the number of elements in the array, it is necessary to start over and begin adding elements starting from the first element. In other words, the third element is added to the first element. The fifth element will be added to the first element; likewise, the sixth element will be added to the second element. This is because an array must consist of a number of elements which is a power of two due to the design procedure which is utilized. Thus N_3 is equal to 120° , since K_2 was chosen to be $\frac{1}{2}$. If K_2 had been chosen a different value, the position of element N_3 would of course be different.

$$(24) \quad N_4 = N_2 + \frac{1}{2K_2}$$

$$(25) \quad N_5 = N_1 + \frac{1}{2K_3}$$

$$(26) \quad N_6 = N_2 + \frac{1}{2K_3}$$

$$(27) \quad N_7 = N_3 + \frac{1}{2K_3}$$

$$(28) \quad N_8 = N_4 + \frac{1}{2K_3}$$

$$(29) \quad N_9 = N_1 + \frac{1}{2K_4}$$

.....

$$(30) \quad N_{16} = N_8 + \frac{1}{2K_4}$$

$$(31) \quad N_{17} = N_1 + \frac{1}{2K_5}$$

.....

$$(32) \quad N_{32} = N_{16} + \frac{1}{2K_5}$$

and so on.

The reader, by examining these equations, will readily perceive that they are simply special cases of Equations 19, 20 and 21 which define the procedure for calculating the additional elements of the array. Thus, when the array reaches 4 elements, the fifth element is calculated using the third value, K_3 , for the design parameter K. Likewise when the array reaches 8 elements, to add the ninth element, the next arbitrary value K_4 for the design value K is used. Here K_3 is equal to 2 and K_4 is equal to 4. The only limitation on the choice of the design values K is that they be numbers greater than one, this is to keep the design normalized with K_1 equal to 1. Other than that, K values may be chosen as integers, fractions, irrational numbers and so on.

This also provides an opportune place to point out the distinct advantage of my design procedure. Suppose,

for example, that the design of an array is proceeding and three values of K have been chosen, namely, K_1 equal to 1, K_2 equal to $\frac{1}{2}$, and K_3 equal to 4. There are now eight elements in the array, it is desired to add eight more elements and create a 16 element array. An inspection of the plot for the eight elements reveals that it would be desirable to place K_4 equal to 2. This is readily done and creates no difficulty whatsoever. The 16 element array which results will be exactly the same as that shown in Table I and it makes no difference in what order the particular values of the K's are chosen. The reader can readily verify this for himself by calculating the elements using the same set of K values but in a different order.

If the four values for K are chosen as 1, $\frac{1}{2}$, 4 and 2 in any order, the numbering of the elements will change in general. However, the relative spacing of the 16 elements will result in an array that is exactly identical to that shown in FIGURE 2 for any ordering of the design K's. This can be verified by the reader himself in a few moments of calculation.

Thus, at each step in the array, if the array is increased in size, the designer can review the radiation pattern produced by the number of elements used up to that point and he can pick the additional elements and place them so as to provide an improvement in the radiation pattern and never a degradation. This is a distinct advantage over the prior art design procedures. The addition of more elements to the array always improves the radiation pattern and can never degrade it.

Likewise, there is another feature of great importance in my method of building antennas. Suppose that an array is to be made up of 32 elements. Using the procedures outlined above, the first 16 elements of the array are calculated and their locations noted. Now, one more value for K_5 is to be chosen. If the first four K values are not changed, the position of the first 16 elements of the array is in no way affected by the addition of the next 16 elements. Thus the beneficial results obtained from the first part of the calculations will never be lost or degraded by the addition of additional elements to the array. This is an unusual result and obviously extremely advantageous. Those skilled in the art will appreciate the design and practical advantages of being able to add elements to an array with an assurance that the pattern already obtained can not be degraded, but only improved by the addition of more elements. An example will be given in connection with FIGURE 6 which shows a 32 element array.

I have now explained my design procedure and the process for determining the coded spacings for my antenna elements. For future reference, I now tabulate in algebraic form the general equations for calculating the positions of the elements of an array up to and including 64 elements, that is, 2 to the power 6, which allows the choice of six values for K, the arbitrary design factor. These equations are simply Equations 19, 20 and 21 written out in algebraic form where each previous element is kept in the algebraic form involving the previous design values chosen for K. These 64 equations are unchanging and they present the general equations for calculating the position of any size array up to 64 elements, that is an array of 2, 4, 8, 16, 32, or 64 elements. The actual positions, of course, depend upon the values chosen for the design parameter K. Although the 64 equations presented here, numbered 33 through 96, appear to be in a rather awkward form, actually there is a practical advantage in presenting these calculations in this manner, rather than using the simpler form of calculation indicated by equations, such as 19. This will be pointed out in particular with reference to FIGURE 10 which shows the left half of a 64 element array.

Returning now to FIGURES 2 and 3, FIGURE 3 shows the plot of the radiation intensity E_t of the antenna of FIGURE 2, plotted versus the design factor K. It should be stressed that this plot is in K and not yet in

space angle θ which will illustrate another important advantage of our method and system. It can indeed be seen that nulls occur in this pattern, that is, zero values of radiation at values of K equal to 1, 2, 1½, and 4, as was indicated by our original choice of the values of K_1 , K_2 , K_3 , and K_4 . In general, one of the advantages of our design procedure is to form the design using plots, such as FIGURE 3, where the abscissa is in units of K . This greatly facilitates the design, and it results in a normalized design which can be adapted for a number of other conditions by certain physical spacing when it is actually constructed.

It may be noted in FIGURE 3, that the central lobe is extremely sharp and contains a large percentage of the total energy emitted from the array. The total integrated area under the graph represents the total energy emitted by the 16 elements of the antenna of FIGURE 2. Once a particular code has been picked, utilizing given values for K , the radiation pattern can be plotted in terms of K by utilizing Equation 3 which is now re-written as Equations 98A, 98B and 98C.

$$(98A) \quad E_t = e^{iN_1\psi} + e^{iN_2\psi} + e^{iN_3\psi} + \dots e^{iN_m\psi}$$

(98B)

$$E_t = [(\cos N_1\psi + \cos N_2\psi + \dots \cos N_m\psi) + j(\sin N_1\psi + \sin N_2\psi + \dots \sin N_m\psi)]$$

$$(98C) \quad E_t = \sqrt{\left(\sum_{\text{all } N} \cos N\psi\right)^2 + \left(\sum_{\text{all } N} \sin N\psi\right)^2}$$

where $\sum_{\text{all } N}$ signifies the summation for all n terms present in the code.

The values $N_1\psi$, $N_2\psi$ for example, are the normalized electrical degrees, such as shown in Table I, and the cosines and sines may be taken directly from tables, or by calculation. The pattern must be summed up for all of the N elements in the array as indicated in Equation 98C. Also, since $N\psi = N(360)K$, Equation 99 can be written:

(99)

$$E_t = \sqrt{\left(\sum_{\text{all } N} \cos N(360)K\right)^2 + \left(\sum_{\text{all } N} \sin N(360)K\right)^2}$$

In Equation 99, E_t is given as a function of K . To form the plot, a value for K is picked, then Equation 99 is calculated and yields a value for E_t . Then K is increased a convenient increment and Equation 99 is recalculated for the new value of K , and so on, for the particular array which has the fixed relative spacing depending upon the design parameters of the constants K_1 , K_2 , K_3 etc. which have been chosen. This plot of E_t versus K is shown for the array of FIGURE 2 in the illustration of FIGURE 3. To evaluate Equation 99, only values of K within a region up to a value of K_{MAX} equal to $1/\sin \theta_0$ need be chosen.

In FIGURE 4, the radiation pattern of the antenna of FIGURE 2 has been shown plotted against θ , the physical space angle. To form this plot $\sin \theta_0$ was chosen as equal to $\frac{1}{6}$. In other words, θ_0 equals 9.6° . This represents the width of the first lobe, or the main lobe, that is, the point along the θ axis where the first null occurs, as shown on the diagram. It should be noted that, since $\sin \theta$ is equal to $K \sin \theta_0$, there is no linear correspondence between the values of K and the values of θ , even for a fixed value of θ_0 . This is because θ and $K \sin \theta_0$ are related by the sum of θ and not one to one. This causes no computations difficulties, however. It should also be noted that a variation of θ through 90 physical degrees is sufficient to specify the full performance of the antenna pattern as was mentioned previously. An examination of FIGURE 3 shows that nulls occur in fact at values of K equal to 1, $\frac{3}{2}$, 2 and 4. This is as expected, since these points were picked to be forced nulls according to the principle of my method of designing array antennas.

FIGURE 5 shows a second embodiment of my invention which illustrates the extreme practical utility of my antenna arrays and the method of building them. The figure shows a similar coded array, as in FIGURE 2, extended into a two dimensional array. It is a plan view of the array, and the individual antenna elements have been simply shown as dots for convenience. The correct relative proportions are shown and the scale is the same as in FIGURE 2. FIGURE 5 was created from FIGURE 2 with no further computation. The array antenna of FIGURE 5 provides an antenna radiation pattern in three dimensions in space, that is, not only does it provide the radiation pattern shown in FIGURE 4 in the plane of the axis of the array of FIGURE 2, but it provides this same pattern in a plane perpendicular to the plane containing the axis of the 16 elements of FIGURE 2.

An inspection of FIGURE 5 will quickly reveal its pattern. The first row across, consisting of 16 individual antenna elements, which might be dipoles, dicones, horns etc. or whatever is convenient, are numbered 1 through 16 and are numbered corresponding to FIGURE 2. It will be seen that the second row of antenna elements, relative to each other, is spaced exactly the same way as the first row. Thus, element 19 which is the first element of the second row is 45 electrical degrees from element 20 which is the second element of the second row. Likewise element 21 is exactly 45 electrical degrees from element 20, just as element 5 is 45 electrical degrees from element 9 in the first row. However, the entire second row, such as elements, 19, 20, 21, 22 and so on, is spaced the same distance from the first row as element 9 is spaced from element 1, namely 45 electrical degrees. The first element of the third row, element 23, is the same distance from element 19 as element 5 is from element 9 in the first row. Likewise element 24, which is the first element of the fourth row, is the same distance from element 23, as element 3 is from element 5 in the first row. Also element 25, which is the second element in the fourth row, is the same distance from element 24 as element 9 is from element 1 in the first row. The pattern is extended in this manner, as shown, as it will be seen that along any line of elements, either horizontal or vertical, the relative spacing is exactly the same as that shown in FIGURE 2 or the first row in the array of FIGURE 5.

Thus, the spacing of the array along a single axis, such as shown in FIGURE 2, in actuality also completely spaces the location of all the elements of a square array consisting of $n \times n$ elements, where n is the number of elements in the single axis array. The total number of elements, shown in FIGURE 5, is 16 squared, that is, 256 elements.

This property of my antenna arrays, that they may be reproduced in two dimensions to create a three dimensional antenna radiation pattern is obviously of great practical utility and is true of all antenna arrays created according to my method, and accordingly the embodiments of FIGURES 6 and 10 also may be extended in two directions in the same manner.

For convenience of illustration, I have only shown the embodiments of FIGURES 6, 8 and 10 along a single axis. But the embodiments of FIGURES 6, 8 and 10 may likewise be extended into a two dimensional square array in the same manner, and I claim such two dimensional arrays as part of the novelty of my invention.

Just as in FIGURE 2, the antenna elements of FIGURE 5 should be supplied with equal amounts of power from a source providing the same phase of signal to each of the elements. For convenience, the translation device, such as 17, has not been shown in FIGURE 5b.

For such a relatively large array as is shown in FIGURE 5, it may be more convenient if a separate power transmitting stage is connected to each of the elements and supplied with a low power level signal from the same local oscillator, for example, as indicated schematically in FIGURE 5b.

FIGURE 5b merely illustrates what has been mentioned before, that each of the individual antenna elements of my array, such as N_1 or N_9 or N_7 can be individually supplied with a high power transmitting stage for sending purposes for use of the array as a transmitting antenna and with an individual amplifier for using the array for receiving purposes. Each of the power transmitting stages, such as 26, 27, 28, and so on, can be exactly identical in design; each transmitting stage, such as 26, supplies the same amount of power to its individual antenna element as all the other transmitting stages. Thus, these transmitting stages might consist of an individual travelling wave tube, for example, with an associated power supply and frequency control circuits. As a result, these individual transmitting stages can each be made to operate at its peak point of design efficiency, and there is no necessity for wasting RF power in power dividing networks for providing unequal amounts of power to the individual elements.

Likewise for receiving purposes, if desired, each individual antenna element such as N_1 may be provided with a high gain, low noise amplifier, such as 29, 30, and 31. Each of these amplifiers is exactly the same as the others and provides an equal amount of gain. This also allows the output from each individual antenna element to be amplified immediately before passing to the connecting lead networks such as 32, where it is connected to the input of the rest of the receiver equipment.

Obviously, if desired, the amplifier, such as 29, and transmitting stage, such as 26, may be omitted and the array of FIGURE 5 may be supplied with one single transmitting or receiving apparatus, as indicated in FIGURE 2, by the use of multiple feed lines, such as shown as 18, 18a, 18b, and so on. Whichever is most convenient for a particular application will be used. The individual amplifiers and transmitting stages, such as 26 and 29, can be physically disposed extremely close to the individual antenna elements in the arrays built according to my method.

Refer now to FIGURE 6, which shows the correct relative spacing for an array antenna built according to my method and composed of 32 individual antenna elements, spaced according to Table II.

TABLE II

Code No. 2 (shown in FIGURE 6)

32 element code with forced nulls chosen at:

$K_1=1$	$K_3=2$	$K_5=\frac{5}{4}$
$K_2=\frac{3}{2}$	$K_4=4$	
$N_1=0^\circ$	$N_9=45^\circ$	
$N_2=180^\circ$	$N_{10}=225^\circ$	
$N_3=120^\circ$	$N_{11}=165^\circ$	
$N_4=300^\circ$	$N_{12}=345^\circ$	
$N_5=90^\circ$	$N_{13}=135^\circ$	
$N_6=270^\circ$	$N_{14}=315^\circ$	
$N_7=210^\circ$	$N_{15}=255^\circ$	
$N_8=390^\circ$	$N_{16}=435^\circ$	
.....	.....	.....
$N_{17}=144^\circ$	$N_{25}=189^\circ$	
$N_{18}=324^\circ$	$N_{26}=369^\circ$	
$N_{19}=264^\circ$	$N_{27}=309^\circ$	
$N_{20}=444^\circ$	$N_{28}=489^\circ$	
$N_{21}=234^\circ$	$N_{29}=279^\circ$	
$N_{22}=414^\circ$	$N_{30}=459^\circ$	
$N_{23}=354^\circ$	$N_{31}=399^\circ$	
$N_{24}=534^\circ$	$N_{32}=579^\circ$	

An inspection of Table II will reveal an advantageous feature I have stressed previously, namely, that since the first four values of K are the same as those shown in Code No. 1 in Table I, the first 16 values of Code No. 2 are exactly the same and need not be recalculated when building up Code No. 2 with a 32 element array. The fifth value K_5 has been chosen as $\frac{5}{4}$. The quan-

70 tity $\frac{1}{2}K_5$ is thus equal to 144 electrical degrees and the 16 new values for Code No. 2 may be formed by adding 144° increments to the appropriate terms in Code No. 1, as has been outlined in the previous development, particularly Equations 19, 20 and 21. Alternatively, the code element positions may be calculated, using Equations 33 through 55.

FIGURE 7a shows the first part of the plot of the radiation intensity E_t versus the design parameter K of the antenna of FIGURE 6. FIGURE 7b shows the same antenna array plotted out to values of K_{MAX} equal to 30. FIGURE 7c will be seen to be an expanded version near the origin of FIGURE 7b. FIGURE 7c also shows Code No. 1 having 16 elements and Code No. 2 with 32 elements plotted on the same scale for comparison.

It is important to point out at this time a further additional advantage of my method of building antennas. My design, as so far explained, permits a given number of values for the design parameter K to be chosen in an arbitrary manner, depending upon the number of elements in the array. At these chosen values of K , such as K_1 , K_2 , K_3 and so on, there will be zero radiation in space at the corresponding space angle θ . It can now be stated that in addition there will be a null at every odd integral multiple of the chosen values of K . Thus, if K_1 is equal to 1, nulls will also be produced at values of K equal to 3, 5, 7 and so on. Likewise if K_2 is chosen to be $\frac{3}{2}$, there will be nulls produced at 4.5, 7.5 and so on. Inspection of FIGURE 3 will 30 clearly reveal these nulls which have been circled lightly with dotted lines. This property of the presence of nulls at all odd integral values for all the chosen values of K , in effect allows double duty to be performed by the chosen values of K .

35 The values of K which are chosen depend on what type of radiation pattern is to be produced. In the examples given so far, the antenna radiation pattern has been of the type where it is desired to produce a central lobe which has as high a maximum value relative to 40 the side lobes as possible. In addition the central lobe is intended to be as narrow in angular degrees as possible. Further, the amplitude of the second and third side lobes is intended to be as low as possible, and, in addition, the occurrence of the second and third side lobes is intended to be pushed out as far in angular degrees as possible.

45 By comparing FIGURE 3 with FIGURE 7a, and by referring to FIGURE 7c, which is the combined plots of FIGURE 7a and FIGURE 3, the effect of adding 16 50 additional elements in Code No. 2, to produce an array having 32 elements can be appreciated. Thus, in FIGURE 3, the peak of the first side lobe occurred approximately at a value of K equal to 1.25, as can be seen. Note, that in Code No. 2, FIGURE 7a, K_5 was chosen 55 to be equal to 1.25, that is, $\frac{5}{4}$. Thus, a new additional null was chosen to be right in the middle of the first side lobe. In effect this squashed down the first side lobe. Examining FIGURE 7a near the region θ_0 , it can be seen that the first side lobe, and in fact the second side lobe, 60 have virtually disappeared, their amplitude being so small relative to the main lobe that it is difficult to show it.

65 It can also be seen in FIGURE 7a that an additional null has been produced at K equal to 3.75. This is 3 times 1.25. This additional null at 3.75 had the effect of considerably reducing the magnitude of the fourth side lobe, as can be seen on FIGURE 7c, by comparison of the two curves.

70 Also note in FIGURE 7c that the sharpness of the main lobe of the 32 element array of Code No. 2 has also been improved.

75 It can be appreciated that Code No. 2 has greatly improved the radiation pattern by the addition of more elements in a controlled manner chosen at the designer's will. Likewise, I wish to point out that antenna radiation patterns of virtually arbitrary shape can be pro-

duced by my method. For example, it may be desired to concentrate a side lobe power in some angular region in space that is in a certain range of values for θ . To do this, it is only necessary to place nulls outside of this region before the beginning of the region and after the end of the region, the resulting power then must appear in the region where nulls were not chosen. In other words, by being able to choose points in space that have nulls, in effect the maximums of the radiation pattern must exist in other regions in space, since the total energy supplied to the antenna cannot change, and in effect the designer can locate maximums of radiation by specifying where the minimums occur.

I now wish to point out another feature of my invention which is quite convenient from the viewpoint of physical construction and also as a check of the accuracy of computations. Examination of FIGURE 2 will show that it is precisely symmetrical about the point located at 217.5° . This is exactly the middle of the array, the furthermost element N_{16} being located at 435 electrical degrees. This physical symmetry is always produced, although the equations given would not indicate it by themselves.

This physical symmetry of the codes also indicates that the method of derivation rests on solid physical foundations, because, as noted, the space angle θ has only been considered over 90° , since the array was stated to be one which will produce symmetrical radiation patterns to begin with. Likewise, in computation, when an array has been completed, if its is plotted out to scale, as shown in FIGURES 3, 5, 8 and 10, and, in fact, the antenna pattern is not symmetrical, then a mistake has been made in the calculations.

This may suggest to the reader a method of saving computations by computing only the equations necessary for one half of the array and then simply duplicating the array about the axis of symmetry. Unfortunately, however, it is not usually readily apparent which particular elements will lie on one particular side of the array; this is because physically, as the elements are calculated, they are interleaved with the previous existing elements of the previous array and as a result a higher numbered element does not necessarily lie farther from the first element than a corresponding lower numbered element. Thus, for example, element N_9 is actually much nearer to element N_1 than element N_3 is, and so on.

However, once the array has been calculated completely, the relative spacing may be arranged arbitrarily in increasing order of distance from the first element N_1 . Then the first half of the set of values may be plotted out, and this will produce the first half of the antenna. The second half of the antenna will be exactly similar to this and in fact be the mirror image.

FIGURE 8 shows another embodiment of my invention also utilizing a 16 element array. However, the values of K chosen for this array are different from that shown in Code No. 1. The antenna utilizing Table III with Code No. 3 has been drawn in FIGURE 8 to scale and the resulting radiation pattern as a function of K is shown in FIGURE 9.

TABLE III
Code No. 3

16 element code with forced nulls chosen at:

$K_1=1$	$K_3=\frac{3}{2}$
$K_2=\frac{5}{4}$	$K_4=\frac{11}{6}$
$P_1=0^\circ$	$P_9=278.18^\circ$
$P_2=98.18^\circ$	$P_{10}=300^\circ$
$P_3=120^\circ$	$P_{11}=324^\circ$
$P_4=144^\circ$	$P_{12}=362.18^\circ$
$P_5=180^\circ$	$P_{13}=398.18^\circ$
$P_6=218.18^\circ$	$P_{14}=422.18^\circ$
$P_7=242.18^\circ$	$P_{15}=444^\circ$
$P_8=264^\circ$	$P_{16}=542.18^\circ$

It will be seen that two of the K values are the same, namely, 1 and $\frac{3}{2}$. However, in Code No. 3, FIGURES 8 and 9, K_2 has been chosen as $\frac{5}{4}$ and K_4 has been chosen at $\frac{11}{6}$. It can be seen from inspection of FIGURE 9 that the first side lobes have immediately been tremendously reduced by this expedient. In Table III presenting Code No. 3, I have simply presented the relative spacing location of the elements in order of increasing value, their computation is exactly the same as that given in Equations 19, 20 and 21, but the element numbering according to the equations has not been preserved. To distinguish that the elements are arranged simply in order of increasing physical location, I have labeled the locations as P_1 , P_2 and so on, in Table III.

FIGURE 10 shows a preferred embodiment of my invention. Table IV gives Code No. 4 which gives the relative physical spacing which was plotted to scale in FIGURE 10.

TABLE IV

Code No. 4

64 element code with forced nulls chosen at:

$K_1=1$	$K_3=\frac{4}{3}$	$K_5=\frac{11}{6}$
$K_2=\frac{7}{6}$	$K_4=\frac{3}{2}$	$K_6=\frac{5}{2}$
$P_1=0^\circ$	$P_{33}=387^\circ$	
$P_2=72^\circ$	$P_{34}=387.46^\circ$	
$P_3=98.18^\circ$	$P_{35}=398.18^\circ$

The antenna radiation pattern as a function of K has been given in FIGURE 11 for the antenna shown in FIGURE 10 and Table IV, and FIGURE 12 shows the antenna radiation pattern as a function of the physical space angle θ for a value of $\sin \theta_0$ equal to $\sin \frac{1}{6}$, namely 9.6° . An inspection of FIGURE 12 will immediately make apparent to those that are skilled in the antenna art that this antenna radiation pattern is quite unusual. It can be seen that the main, that is the central lobe, is quite sharp in angular degrees and in fact the width of the main beam at the one half power point is only 5 angular degrees. In addition, the first two side lobes are so low in magnitude they can hardly be plotted to the same scale as the main lobe. Further, the first side lobe which has any appreciable amplitude, the third side lobe, has been physically moved out to the region beyond 20° . Such an antenna has an extremely sharp beam which would be excellent, for example, for tracking radar service or highly

directional communication systems. It will also be appreciated that an extremely high percentage of the antenna power is disposed in the main beam and the amplitudes of all the side lobes are extremely low.

In Table IV, the values for the relative spacing for Code No. 4 have been tabulated in order of increasing size and the original identification, according to equations, such as 19, has not been retained.

In FIGURE 10, for convenience of illustration, I have utilized the property of symmetry of the antenna array and have presented only slightly more than one half of the actual array. Elements P_1 through P_{39} have been plotted on correct relative scale in FIGURE 10. The axis of symmetry is located at 379.73° . This is one half the value of the location of the 64th element P_{64} at 759.46° . It can be seen in FIGURE 10 near the axis of symmetry that in fact the array is symmetrical and the right hand side of FIGURE 10, if continued, would be the exact mirror image of the left hand side. Exactly half the elements lie on each side of the axis of symmetry. The exact location of all the elements can be determined, of course, from Table IV.

As before, equal amounts of power at the same phase are fed to each of the 64 individual antenna elements of the embodiment of FIGURE 10. The arrangement similar to that shown in FIGURE 5 or the scheme shown in FIGURE 2 may be used, whichever is most convenient.

FIGURE 12 shows the radiation pattern in actual physical space for a chosen value of θ_0 equal to 9.6° angular degrees. FIGURE 11 illustrates the plot of the radiation pattern versus the design parameter K . It can be seen that for values of K up to approximately 9, the response of the antenna is excellent, as indicated by the extremely small magnitudes of the early order side lobes. The first two side lobes have been virtually suppressed completely.

It might also be pointed out that Code No. 4 is not an extension of Code No. 2, because the K values are in general not the same. New values of K for K_2 equal $\frac{1}{6}$, K_3 equal $\frac{1}{6}$, K_5 equal $1\frac{1}{6}$, and K_6 equal to $\frac{5}{2}$ were chosen to create the array of FIGURE 10. Thus the array had to be calculated completely from the beginning of the first element because, in general, the positions were not the same as in the other code shown.

It may also be pointed out that Equations 19, 20 and 21 may be used to build up an array, such as Code No. 4. However, in the case of a relatively large array, such as shown in Code No. 4, I recommend the use of the sequence of equations following Equation 32 (most of which have not been given) but which would be numbered 33 through 96. The reason is this: equations, such as 33 through 96, present the calculations of the position of each element in the array as a number of factors which are divided by a product. Thus, in using these equations, there is only one error introduced by rounding off after the final calculation; however, if equations, such as 19, are used, each time a new value of K is chosen, for example when K_3 is chosen, $\frac{1}{2}K_3$ will have to be rounded off for an actual calculated value. Then when the array is increased to 16 elements, $\frac{1}{2}K_4$ must be calculated. Again, the quantity $\frac{1}{2}K_4$ must be rounded off, and this will introduce a very small but cumulative error into the positions in the array. Since by using equations such as 19, all the following later elements in the array are located according to the previous elements, these additions of calculation errors will become cumulative and, for a very large array, they can conceivably result in cumulative errors which would represent a large fraction of a wavelength of the antenna. Hence, the calculation procedure indicated in Equations 33-96 avoid any cumulative error and results in only one error at the end of each calculation.

For arrays where the frequency is such that the wavelength is relatively long, the Equations 19 through 21 will serve equally well. Mathematically, the positions are exactly the same no matter which procedure is used.

I also wish to point out another feature of my linear

array antennas. Any of my linear arrays, shown or produced by my method, may be electronically "steered." By this I mean that, instead of introducing the signals in each antenna at the same phase, a progressive phase delay or shift may be introduced between the feeds to the various elements. This technique in itself is well known in the prior art. This will have the effect of shifting the radiation patterns of the antenna along the axis. Likewise if the phase shifts are successively changed in time along the array, the antenna pattern can be made to move in space, this is, to point the beam in different directions. This is a very advantageous feature of my linear array antennas, but it does not in itself form any part of the novelty of my invention.

Likewise I wish to point out that if individual antenna elements are used, which in themselves have a highly directional characteristic, the overall antenna radiation pattern, due to my array, will simply be the multiplication of my radiation patterns, such as shown in FIGURE 12 or 11, by the individual directional characteristic of the individual elements. This is also highly useful, in that, if directional elements are used to compose the array, the overall response can be obtained with a relatively small amount of calculation. This, in itself, does not form part of the novelty of our invention however.

While I have described above the principles of my invention in connection with specific apparatus and method steps, it is to be clearly understood that this description is made only by way of example and not as a limitation 30 to the scope of my invention, as set forth in the objects thereof and in the accompanying claims.

What I claim is:

1. A linear array antenna comprising N individual elements, where N is an integral power of the base 2, and 35 means for supplying the same amount of power in the same signal phase to each of said N individual elements, the spacing between said individual elements being determined by the values selected for $K_{(x+1)}$, where K is a design parameter and is the ratio of the sine of any particular value of the space angle θ , formed by the axis of the antenna array and a line drawn from the array, divided by the sine of the particular space angle where the null of the main lobe of the antenna radiation pattern occurs; said spacing also being determined according to the equations

$$N_{(2^x+1)} = N_1 + \frac{1}{2K_{(x+1)}}$$

$$N_{(2^x+2)} = N_2 + \frac{1}{2K_{(x+1)}}$$

.....

$$N_{(2^x+2^y)} = N_{(2^y)} + \frac{1}{2K_{(x+1)}}$$

55 where the subscript of N identifies the coded position of that particular element of said N elements and X is an index number assuming values 1, 2, 3, 4, etc.

2. A method of securing a predetermined directive radiation pattern for a linear array antenna comprising N individual antenna units, where N is an integral power of the base 2 and where each of said individual antenna elements is supplied with the same amount of power at the same signal phase, said method comprising adjusting the relative spacing between said individual antenna elements 60 according to the equations

$$N_{(2^x+1)} = N_1 + \frac{1}{2K_{(x+1)}}$$

$$N_{(2^x+2)} = N_2 + \frac{1}{2K_{(x+1)}}$$

.....

$$N_{(2^x+2^y)} = N_{(2^y)} + \frac{1}{2K_{(x+1)}}$$

75 where $K_{(x+1)}$ is a selected design parameter and K is the

ratio of the sine of any particular value of the space angle θ , formed by the axis of the antenna array and a line drawn from the array, divided by the sine of the particular space angle where the null of the main lobe of the antenna radiation pattern occurs and where the subscript of N identifies the coded position of that particular element of said N elements and X is an index number assuming values 1, 2, 3, 4, etc.

3. A method of securing an exceedingly sharp central lobe and arbitrarily small side lobes for a linear array antenna having N antenna elements, where N is an integral power of two, said method comprising spacing individual antenna units unequally from each other according to a predetermined code given by the equations

$$N_{(2^x+1)} = N_1 + \frac{1}{2K_{(x+1)}}$$

$$N_{(2^x+2)} = N_2 + \frac{1}{2K_{(x+1)}}$$

$$N_{(2^x+2^y)} = N_{(2^x)} + \frac{1}{2K_{(x+1)}}$$

where the subscript of N identifies the coded position of that particular element of said array, $K_{(X+1)}$ is a predetermined design parameter and K is the ratio of the sine of any particular value of the space angle θ , formed by the axis of the antenna array and a line drawn from the array, divided by the sine of the particular space angle where the null of the main lobe of the antenna radiation pattern occurs, and where X is an index number assuming the values 1, 2, 3, 4, etc.

4. A method of securing a predetermined directive radiation pattern for a linear array antenna comprising N individual antenna units, where N is an integral power of the base 2, said method comprising adjusting the relative spacing between said individual antenna elements according to the equations

$$N_{(2^x+1)} = N_1 + \frac{1}{2K_{(x+1)}}$$

$$N_{(2^x+2)} = N_2 + \frac{1}{2K_{(x+1)}}$$

$$N_{(2^x+2^x)} = N_{(2^x)} + \frac{1}{2K_{(x+1)}}$$

where $K_{(X+1)}$ is a selected design parameter and K is the ratio of the sine of any particular value of the space angle θ , formed by the axis of the antenna array and a line drawn from the array, divided by the sine of the particular space angle where the null of the main lobe of the antenna radiation pattern occurs and where the subscript of N identifies the coded position of that particular element of said N elements and X is an index number assuming values 1, 2, 3, 4, etc.

10 5. A linear array antenna comprising N individual elements, where N is an integral power of the base 2, and means for supplying power to each of said N elements, the spacing between said individual elements being determined by the values selected for $K_{(x+1)}$, where K is a design parameter and is the ratio of the sine of any particular value of the space angle θ , formed by the axis of the antenna array and a line drawn from the array, divided by the sine of the particular space angle where the null of the main lobe of the antenna radiation pattern occurs,
15 20 said spacing also being determined according to the equations

$$N_{(2^x+1)} = N_1 + \frac{1}{2K_{(x+1)}}$$

$$N_{(2^x+2)} = N_2 + \frac{1}{2K_{(x+1)}}$$

$$N_{(2^x+2^x)} = N_{(2^x)} + \frac{1}{2K_{(x+1)}}$$

where the subscript of N identifies the coded position of that particular element of said N elements and X is an index number assuming values 1, 2, 3, 4, etc.
